GEORGE W. BROWN, OF PROVIDENCE, RHODE ISLAND.

Letters Patent No. 92,154, dated July 6, 1869.

IMPROVED SCRUBBING-BRUSH.

The Schedule referred to in these Letters Patent and making part of the same.

To all persons to whom these presents shall come:

Be it known that I, GEORGE W. BROWN, of Providence, in the county of Providence, and State of Rhode Island, have made an invention of a new and useful Scrubbing-Brush; and do hereby declare the following to be a full, clear, and exact description thereof, due reference being had to the accompanying drawings, making part of this specification, and in which—

Figure 1 is a perspective representation, and

Figure 2, a horizontal section of my invention.

This invention relates to means for economizing the waste material, or broom-corn accumulating in broom-manufacturing establishments, by the production of a device for containing and converting into a durable and effective scrubbing-brush, such refuse material, as well as the upper part of old and worn-out brooms.

The invention consists in two clamp-plates, provided with serrated or toothed inner edges, connected together at their extremities by screw-nuts and bolts, and with a handle applied to one at an angle, in order to maintain the brush or scrubbing-material, in an upright position, the whole being as hereinafter explained.

In the drawings above mentioned as illustrating my invention—

a a denote two plates of any suitable material, the outer ends of which are connected together by bolts *b b*, and clamp-nuts *c c*.

The inner edges of these plates *a a*, are serrated, or provided with tapering teeth *d d*, &c., the teeth of one plate being disposed opposite the interstices of its fellow-plate, in order to divide into ridges the broom-corn or other material which is confined between them.

One of the plates *a a*, is provided with a socket, *e*, applied to and extending upward from it at an angle

of forty-five degrees, or thereabouts, such socket being for reception of a handle, shown at *f* in the drawings.

The angular position of the handle upon the plate *a*, enables the brush, while being used for sweeping floors, decks of vessels, &c., to be maintained in an upright position, which greatly increases its effectiveness, and which would not be the case were the handle applied in a straight line with the brush, as is usually the case, and which prevents old brooms from being made effective.

The advantage of my invention consists principally in the fact, that refuse or cheap material, such as waste broom-corn, manilla, and various inexpensive fibrous substances, as well as old brooms which are now valueless, may be made into effective scrubbing-brushes at very low prices.

The employment of the teeth *d d*, &c., upon the plates *a a*, also serves a useful purpose in dividing the mass of corn or other material into ridges. By their peculiar form and arrangement; also, they contribute security to the broom-stuff, to a considerable degree, by reason of a longitudinal pressure conveyed by them in an obvious manner.

What I claim as my improvement is—

The arrangement of the plate *a a*, provided with teeth *d d*, handle-socket and handle *e f*, held together by bolts *b* and thumb-screws *c*, as shown, for the purpose of using waste broom-corn or parts of brooms worn out in ordinary use, as shown and described.

GEORGE W. BROWN.
